UNITED STATES PATENT OFFICE.

CHARLES McCARTER, OF CHATTANOOGA, TENNESSEE, ASSIGNOR TO ROSS MEEHAN FOUNDRY COMPANY, OF CHATTANOOGA, TENNESSEE, A CORPORATION OF TENNESSEE.

CAR-COUPING.

SPECIFICATION forming part of Letters Patent No. 783,884, dated February 28, 1905.

Application filed September 12, 1904. Serial No. 224,137.

To all whom it may concern:

Be it known that I, CHARLES McCARTER, a citizen of the United States, residing at Chattanooga, in the county of Hamilton and State of Tennessee, have invented new and useful Improvements in Car-Couplings, of which the following is a specification.

This invention relates to car-couplings.

The improved car-coupling, which is of the Janney type, involves in its construction a chambered draw-head and a knuckle associated with said head, the knuckle being, as is the custom, movable about a vertical axis. In connection with the knuckle I employ a gravity-dog; and it is the primary object of the invention to maintain the locking-dog positively in its closed, or knuckle-locking; and open, or knuckle-releasing, positions and its travel toward such positions when released by simple and effective means.

It is a further object of the invention to maintain the locking-dog in position to secure the opening of the knuckle and without the necessity of a trainman holding it in such relation, such means being of advantage when it is desired to uncouple two stationary cars.

The invention involves other objects and advantages, which, with the foregoing, will be set forth at length in the following description.

In said description I will set forth in detail that adaptation of the invention which for convenience I have selected for illustration in the accompanying drawings, forming a part of this specification; but I do not limit myself to the showing thus made, for certain variations may be adopted within the scope of my claims succeeding said description.

Referring to the drawings, Figure 1 is a top plan view of a coupling involving my invention, showing by dotted lines an adjacent knuckle, the locking-dog in said figure being in position to free the coöperating knuckle.

Fig. 2 is a horizontal sectional plan view of the coupling, the dog being in its knuckle-locking position. Fig. 3 is a longitudinal sectional elevation of the same, the dog being substantially in the position in which it is represented in Fig. 2. Fig. 4 is a perspec-

tive detail of the knuckle and dog detached and a hub hereinafter described. Fig. 5 is a similar view of the pin for the dog. Fig. 6 is a front elevation of the coupling and a means for operating the dog.

The coupling illustrated in the drawings involves a chambered head, as 2, and a knuckle, 3, the tail portion of which is arranged to be swung into and out of the interior of the head. The knuckle, the working portion of which is of a familiar shape, is pivotally connected with the head for turning movement about a vertical axis, a pin, as 4, of the ordinary kind being represented to secure such action. The locking-dog for the knuckle is denoted in a general way by 5, it being housed within the chambered portion of the head 2 and being held in assembled relation therewith by means of a pivot-pin, as 6, extending vertically through the substantially cylindrical body portion 7 of the locking-dog.

The lower end of the pin 6 is stepped in the bottom of the head, while the upper portion thereof extends through a perforation in the top of said head for turning movement. The intermediate portion of the pin 6 is squared to fit a correspondingly-shaped opening extending depthwise or vertically of the body of the locking-dog.

From the cylindrical body of the locking-dog arms 8 and 9 extend substantially in opposite directions, the arm 8 being straight, 80 while the arm 9 is somewhat curved. The arm 8 terminates at its free end in a lateral lug 10, coöperative with the tail of the knuckle 3. The lug 10 constitutes the effective portion of the knuckle and is shown in its operative position in Fig. 2, at which time it is in the path of the tail of the knuckle, so as to prevent the knuckle from opening. On what might be considered the inner side of the tail portion of the knuckle is a concavity 11, concentric with the axis of motion of the locking-dog when the knuckle is in its normal position, by reason of which construction the locking-dog can be readily opened to effect the release of the knuckle. To release the knuckle, 90 the projection 10 is carried out of the path of

motion of the tail of the knuckle. In Fig. 2 the knuckle is locked closed. When the locking-dog is swung or advanced to the position shown by dotted lines in Fig. 1, it releases the 5 knuckle, and during the motion mentioned the free end of the curved arm 9 is carried against the inner side of the tail portion of the knuckle. On the continued advancing motion of the locking-dog said curved arm will by engaging 10 said tail portion kick or force the knuckle open in an obvious manner.

I will describe the means illustrated for actuating, through the intervention of a trainman, the locking-dog. Upon the end of the car 15 at which the coupling is situated a rock-shaft, as 12, is mounted in some suitable way, it having at its opposite ends cranks or handles 13 and between its ends a third crank, as 14, connected by a suitable connection, as that 20 noted in a general way by 15, with the arm 8 at a suitable distance from the center of motion of the locking-dog. The connection 15 extends through a perforation in the top of the coupling-head. When, therefore, the shaft 25 12 is rocked in the proper direction through the manipulation of one of the cranks or handles 13, the locking-dog 5 will, through the medium of the connection 15, be moved first to the position shown in Fig. 1 from that illustrated 30 in Fig. 2 in order simply to effect the release of the knuckle, or it can be moved further in order to kick or positively open the knuckle by the striking of the curved arm against the outer side of the tail portion of 35 the knuckle. In the construction described there is no strain upon the pin 6 when the coupling is in action, the strain being applied to the locking-lug 10 and being lateral.

Interiorly of the head and rising from the 40 bottom thereof is a hub or hollow boss 16, surrounding the lower portion of the locking-dog pin 6, and the upper portion of which constitutes a seat or support for the cylindrical body of the gravity locking-dog 5 when the latter is in its two extreme shifted positions. On the upper edge of the hub or hollow boss 6 there are illustrated two inclined faces 17 and 18, which converge toward the top of the head. As a matter of fact, the two faces are 45 illustrated as merging at their upper ends. On the lower edge of the cylindrical body of the locking-dog are two correspondingly-inclined faces 19 and 20, coöperative with the faces 17 and 18, but which converge toward the bottom of the head. When the locking-dog 5 is in its operative position, the inclined face 20 thereof will lie solidly against the inclined face 17 of the hub 16, which relation is 50 illustrated in Fig. 4, it being evident that by 60 the engagement of said two faces the locking-dog is held positively against opening movement when the tail of the knuckle presses against the lug 10. By swinging the arm 8 toward the right in Fig. 2 to carry the lug 10 65 out of the path of the tail of the knuckle 3

the inclined face 20 will be caused to ride up and then off the inclined face 17, the consequence being that the locking-dog is bodily elevated on its pin 6. When the inclined face 20 passes off the inclined face 17, the lug 10 70 will have passed out of the path of motion of the tail of the knuckle to free the latter. After the face 20 passes off the face 17 the face 19 will be brought into position to ride down the face 18. On the continued swinging movement of the locking-dog the curved arm thereof will be caused to abut against the tail portion of the knuckle to swing said knuckle positively open. The locking-dog 5 is momentarily maintained in its elevated position for 80 a purpose that will hereinafter appear, and when it is released the inclined face 20 can fall against and then down the inclined face 18 by the gravitation of the dog 5, this action occurring during the knuckle-opening action of 85 said dog. When the locking-dog has reached its lower and shifted position, the inclined face 20 will abut solidly against the inclined face 18, the latter serving as a means to prevent accidental closing of the dog. When the knuckle 90 is closed in the customary manner by the coupling of two cars, the tail portion thereof by engaging the arm 9 of the locking-dog swings said dog toward its original position. Initially, therefore, when the dog moves to 95 ward its original position the inclined face 20 rides up the inclined face 18, and when the two faces are out of contact the parts will have reached the position shown approximately in Fig. 1. On the slight further motion of the 100 knuckle in closing the inclined face 20 will be brought into line with the inclined face 17, and when this relation ensues the face 20 can slide down the face 17 by the weight of the dog 5, so as naturally to complete the motion 105 of the locking-dog to its original position independent of the action of the knuckle. The several inclined faces therefore coöperate in 110 positively guiding the dog 5 to its two extreme shifted positions and prevent accidental retractive motion of said dog. By reason of the non-rotative connection between the pin 6 and the locking-dog 5 said dog can be operated from the pin without having recourse to the shaft 12. For this purpose 115 the upper end of the pin has a handle, as 21, by which the pin can be turned in order to correspondingly turn the locking-dog. I have hereinbefore set forth the procedure 120 that is usually followed in opening the knuckle 3 when the same is not connected with a like knuckle. In such a case as this it is desirable to mechanically and forcibly open the knuckle after it has been released. In some cases it is only necessary to effect the release of a 125 knuckle—for example, when the same is coupled to another knuckle. In the latter event the act of separating two cars the couplings of which carry said knuckles effects the opening of the released knuckle, and I provide 130

means for positively holding the locking-dog elevated and in its knuckle-releasing position, so that a trainman need not remain at hand for this purpose. Upon the tail portion of the 5 knuckle, near the hub thereof, is a horizontal ledge or projection 22, coöoperative with the free end of the curved arm 9. When the locking-dog 5 is turned and necessarily elevated to free the knuckle in the manner hereinbefore 10 described, the curved arm 9 will ride over the upper side of the ledge or projection 22 just after the inclined face 20 passes off the inclined face 17, as indicated in Fig. 3, to positively uphold the dog or prevent its accidental 15 return to its knuckle-locking position. When the knuckle is opened by the act of separating two cars, the ledge or projection 22 is carried from off the arm 9 to release the dog 5, so that the same can drop to carry the face 19 against 20 and then down the face 18, the motion being completed when the knuckle has been opened wide. If through any cause the dog 5 should be in its closed or knuckle-locking position while the knuckle is open, the tail portion of 25 the knuckle will in the act of closing strike the lug 10 and will swing the arm 8, carrying said lug, toward the right in Fig. 2, the face 20 during this action riding up the face 17 a distance sufficient to permit the knuckle to 30 fully close. When the knuckle is fully closed, it frees the dog, so that the latter by gravity can resume quickly its knuckle-locking position. In some cases the knuckle when released may be opened by direct manipulation.

35 It is not necessary that I should employ all the features hereinbefore described, for in certain cases some of them may be omitted.

In Figs. 3 and 4 I have illustrated the locking-dog and coöperating hub constituting part 40 of the draw-head as having each only a pair of inclined faces. I have adopted this simply for convenience and to avoid confusion in illustration. In Fig. 2 I have illustrated the two parts as each having two pairs of cam-faces.

45 Having thus described my invention, what I claim is—

1. In a car-coupling, a draw-head and a knuckle therein, combined with a gravity locking-dog for the knuckle, having oppositely-inclined faces, the draw-head having coöperating inclined faces to maintain the locking-dog in its closed and open positions respectively, and to guide it toward such positions.

2. In a car-coupling, a draw-head and a 55 knuckle therein, combined with a gravity locking-dog for the knuckle, having oppositely-inclined faces, the draw-head having coöperating inclined faces to maintain the locking-dog in its closed and open positions respectively and to guide it toward such positions, and a pivot-pin for the gravity locking-dog, non-rotatively associated therewith and having means for its manual operation.

3. In a car-coupling, a draw-head and a 60 knuckle therein, combined with a gravity lock-

ing-dog for the knuckle, having oppositely-inclined faces, the draw-head having coöperating inclined faces to maintain the locking-dog in its closed and open positions respectively, and to guide it toward such positions, and a 70 pivot-pin for the locking-dog, having a squared shank, the locking-dog having a correspondingly-shaped opening to receive said shank, said pin having a handle at its upper end for its manual operation.

4. In a car-coupling, a draw-head and a knuckle therein, combined with a gravity locking-dog for the knuckle, having oppositely-inclined faces, the draw-head having coöperating inclined faces to maintain the locking-dog 80 in its closed and open positions respectively, and to guide it toward such positions, said dog being arranged to occupy an elevated position to free the knuckle, and means for temporarily holding the dog in said elevated 85 position.

5. In a car-coupling, a draw-head and a knuckle therein, combined with a gravity locking-dog for the knuckle, having oppositely-inclined faces, the draw-head having coöperating inclined faces to maintain the locking-dog 90 in its closed and open positions respectively, and to guide it toward such positions, said dog being arranged to occupy an elevated position to free the knuckle, and means on 95 the knuckle for temporarily maintaining the dog in its elevated position.

6. In a car-coupling, a draw-head and a knuckle therein, combined with a gravity locking-dog for the knuckle, having oppositely-inclined faces, and a hub in the draw-head upon which the locking-dog rests and having on its upper edge oppositely-inclined faces to coöperate with those on the dog and serving to maintain the locking-dog in its open and closed 100 positions respectively, and to guide it toward such positions.

7. In a car-coupling, a draw-head and a knuckle therein, combined with a gravity locking-dog for the knuckle, having oppositely-inclined faces, the draw-head having rigidly associated therewith coöperating inclined faces to maintain the locking-dog in its closed and open positions respectively and to guide it toward such positions.

8. In a car-coupling, a draw-head and a knuckle therein, combined with a gravity locking-dog for the knuckle, having oppositely-inclined faces, the draw-head having rigidly associated therewith coöperating inclined faces to maintain the locking-dog in its closed and open positions respectively and to guide it toward such positions, said dog, when operated, serving to successively release and then forcibly open the knuckle, and means independent 120 of the dog for causing the opening of the knuckle.

9. In a car-coupling, a draw-head and a knuckle therein, combined with a gravity locking-dog for the knuckle, having oppositely-in- 130

clined faces, the draw-head having coöperating inclined faces rigidly associated therewith to maintain the locking-dog in its closed and open positions respectively and to guide it toward such positions, and means on the knuckle to temporarily hold the locking-dog in an elevated position.

In testimony whereof I have hereunto set my hand in presence of two subscribing witnesses.

CHARLES McCARTER.
